UNITED STATES PATENT OFFICE

SAMUEL H. GIBSON, OF LAKEWOOD, OHIO, ASSIGNOR TO THE FANNER MANUFACTURING COMPANY, OF CLEVELAND, OHIO, A CORPORATION OF OHIO

AGITATOR

Application filed August 22, 1929. Serial No. 387,604.

This invention relates to agitating or mixing devices for use in mixing the contents of a container, and more particularly, to an improved form of agitator of the type to be inserted and operated through a restricted container opening.

An object of this invention is to provide an agitator having a plurality of paddles adapted to be swung from positions along-
10 side the operating shaft to positions substantially at right angles to said shaft, in which one or more of said paddles can be selectively positioned longitudinally of said shaft, and in which means is provided for locking one or
15 more of said paddles in said right angle positions.

The invention may be further briefly summarized as consisting of certain novel combinations and arrangements of parts herein-
20 after described and set out in the appended claims.

In the sheet of drawings forming a part of this application.

Fig. 1 is a vertical sectional view showing
25 the agitator of my invention installed in operative position in a container;

Fig. 2 is a vertical sectional view illustrating the operation of installing my agitator in a container;

30 Fig. 3 is a fragmentary side elevation showing the paddle locking device;

Fig. 4 is a section taken on the line 4—4 of Fig. 3;

Fig. 5 is a view similar to Fig. 4 showing
35 the locking recess of the paddle moved out of engagement with the locking extension; and

Fig. 6 is a detached detail view of the spring latch member.

40 The agitating device of my invention is of the type to be inserted and operated through a relatively restricted container opening, and is accordingly provided with a plurality of paddles which can be moved from a folded position alongside the operating shaft, to an operative position substantially at right angles to said shaft. These paddles, forming a part of my agitating device, are so arranged that the one which is permanently secured at the lower end of the operating shaft stirs up

the solid material at the bottom of the container, while the other paddles are adjustably positioned longitudinally of said shaft to effect a stirring of the contents at various levels within the container.

55

In the drawings illustrating a preferred form of my agitating device, I show a container 10 which may be of any desired size or shape. This container, as is usual, is provided with a threaded opening 11 centrally of the top wall, through which the agitating device may be inserted and operated. The agitating device includes an operating shaft 12, which in this instance, is shown as being square in cross section. At the inner end of this shaft, I provide a socket member 13 which is secured to the operating shaft by means of the pin 14. A propeller-like paddle 15 is pivotally secured to the socket member with the pivot pin 15' arranged to pass through the center of the paddle, so that the paddle is supported upon this pin in a balanced condition, or in other words, in a state of stable equilibrium.

65

With the agitating device in operative position, as shown in Fig. 1, this paddle 15 is suspended close to the bottom wall of the container so that upon being rotated by the actuating shaft, the contents of the container, and especially the material which settles to the bottom, will be effectively mixed and stirred. At various levels above the paddle 15, other mixing paddles 16 may be secured to the shaft.

70

Any suitable number of such paddles may be employed but, in this instance, I have shown two such additional paddles. These additional paddles are similar in shape to paddle 15 but are secured to the operating shaft in a somewhat different manner. For securing each of these paddles to the shaft, I provide a sleeve 17 which can be clamped to the operating shaft at the desired elevation by means of a set screw 18. The sleeve 17 is provided with a square locking extension 19 which extends through an oblong rounded opening 20, formed through the central part of the paddle 16. The opening 20 is so proportioned with respect to the extension 19 that the paddle can be swung upon this extension as a pivot when the paddle is moved from a po-

80

100

sition alongside the operating shaft to a position at right angles to this shaft.

For maintaining each of the paddles 16 in the operative position at right angles to the operating shaft, I provide a locking recess 21 formed adjacent the recess 20 in the central part of the paddle. This locking recess is shaped to correspond with the locking extension 19, and to receive this extension after 10 the paddle has been rotated from the position alongside the operating shaft to the position at right angles to said shaft. For holding the locking recess of the paddle in engagement with the locking projection of the sleeve, I 15 provide a spring latch member 22. This latch member has a square central opening, through which the locking extension extends when the latch member is assembled in position between the paddle and the sleeve, as shown in 20 Figs. 4 and 5. In addition to clamping the sleeve 17 to the shaft, the set screw 18 also retains the paddle on the projection 19. The latch member is preferably formed of resilient material, and is bent to provide a shoulder 25 25, which engages one edge of the paddle when the locking recess is in engagement with the locking projection. When it is desired to release the locking recess from engagement with the locking extension to permit rotation 30 of the paddle, the spring latch member is deflected laterally toward the shaft, which permits the edge of the paddle to move past the shoulder 23, as shown in Fig. 4 of the drawings.

35 For supporting and maintaining the shaft and paddles in position with respect to the axis of the container, I provide an elongated bushing or sleeve 24 which serves as a bearing for the operating shaft. This sleeve is 40 made of a suitable length and is provided with a threaded part 25 at its upper end which can be screwed into the threaded opening 11. The sleeve is also provided with a recess 26 at its upper end into which one end of the operating shaft extends. The bottom of this 45 recess forms a shoulder 27 upon which the shaft and paddles are suspended by means of the washer 28 and the pin 29. An operating handle 30 is provided for turning the shaft and the paddles. This handle is constructed 50 with a socket extension 31 which extends into the recess and fits over the upper end of the operating shaft.

55 In installing the agitating device of my invention in a container, the paddle 15 is swung to a position alongside of the operating shaft, after which the sleeves 17, carrying the additional paddles 16, are slipped onto the operating shaft in succession, and by 60 means of set screws 18 are clamped to the shaft in the desired positions. The paddles 16 are swung about the locking extensions to positions alongside of the shaft, and with the paddles in this position, the device is 65 inserted through the container opening. The

paddle 15, upon striking the bottom of the container, will be rotated to a position at right angles to the shaft where it will remain because of its balanced condition. By lifting up the operating shaft, the paddles 16 can be 70 rotated, in succession, about the locking extensions 19, by causing one end of these paddles to engage the under side of the top wall of the container, as illustrated in dotted line in Fig. 2. Immediately after each paddle has rotated to a position at right angles to the shaft, its engagement with the top wall of the container causes the paddle to be moved bodily downwardly, bringing the locking recess into locking engagement with the projection. Upon lateral movement of the paddle to bring the recess into engagement with the projection, the spring latch member 22 snaps into the position illustrated in Fig. 5, with the shoulder 23 in engagement with the upper 80 edge of the central part of the paddle. The sleeve 24 and the washer 28 are now slipped onto the shaft and the pin 29 is driven through the shaft. The assembled agitator is then lowered into the container and the sleeve is screwed into opening 11, thereby suspending the paddles in proper position. In removing the agitating device from the container, the sleeve 24 is first unscrewed from the opening 11, after which the shaft is lifted 95 and the paddles 16 and 15 are rotated in succession to occupy positions alongside of the shaft to permit their passage through the container opening.

100 It will now be readily seen that with the form of agitator which I have provided, a deposit of material at the bottom of the container will be kneaded and stirred by the paddle 15, while the contents in general, will be thoroughly mixed and stirred by the additional paddles 16. It will also be seen that the sleeve 24 serves as a bearing for maintaining the shaft and paddles in proper position regardless of the position in which the container itself may be.

110 While I have shown and described the device of my invention in a detailed manner, it should be understood, however, that I do not desire to limit myself to the precise details shown and described but, regard my invention as including such changes and modifications as do not involve a departure from the spirit of the invention and the scope of the appended claims.

115 Having thus described my invention, what I claim is:

1. In an agitator of the type to be inserted through a container opening, the combination of a shaft, a plurality of paddles pivotally 125 carried on said shaft and adapted to be swung from a position alongside said shaft to a position substantially at right angles to said shaft, one of said paddles being adjustable longitudinally of said shaft, and means for 130

maintaining said shaft in position with respect to the axis of said container.

2. In an agitator of the type to be inserted through a container opening, the combination of a shaft, a paddle, and a member on said shaft having a projection extending through an opening in said paddle whereby said paddle may be swung from a position alongside said shaft to a position substantially at right angles to said shaft, said projection being shaped for locking engagement with a correspondingly shaped recess adjacent said opening to retain said paddle in said second mentioned position.

15 3. In an agitator of the type to be inserted through a container opening, the combination of a shaft, a paddle, a member on said shaft having a projection extending through an opening in said paddle whereby said paddle may be swung from a position alongside said shaft to a position substantially at right angles to said shaft, said projection being shaped for locking engagement with a correspondingly shaped recess adjacent said 20 opening to retain said paddle in said second mentioned position, and means for holding said paddle with said recess in locking engagement with said projection.

4. In an agitator of the type to be inserted 30 through a container opening, the combination of a shaft, a paddle, a member on said shaft having a projection extending through an opening in said paddle whereby said paddle may be swung from a position alongside 35 said shaft to a position substantially at right angles to said shaft, said projection being shaped for locking engagement with a correspondingly shaped recess adjacent said opening to retain said paddle in said second 40 mentioned position, and a spring latch for holding said paddle with said recess in locking engagement with said projection.

In testimony whereof, I hereunto affix my signature.

45 SAMUEL H. GIBSON.
